[57] CLAIM

The ornamental design for a cab for fire trucks, as shown.

DESCRIPTION

FIG. 1 is a perspective view of a cab for fire trucks showing our new design; it being understood that the broken lines are for illustrative purposes only and form no part of the claimed design;

FIG. 2 is a front elevational view thereof;

FIG. 3 is a side elevational view thereof;

FIG. 4 is a top plan view thereof;

FIG. 5 is a rear elevational view thereof; and

FIG. 6 is a side elevational view thereof, opposite to that shown in FIG. 3.

FIG. 1**FIG. 2****FIG. 3**FIG. 4

FIG. 5

FIG. 6
